C. W. SHARTLE

STOCK BEATER

Filed Sept. 4, 1923

UNITED STATES PATENT OFFICE.

CHARLES W. SHARTLE, OF MIDDLETOWN, OHIO.

STOCK BEATER.

Application filed September 4, 1923. Serial No. 360,845.

This invention relates to improvements in stock beaters for making paper pulp, having particular reference to a type of beater in which the process of reduction is continuous.

In a composite paper stock the raw stock contains, in variable percentages, two general grades of material,—non-fibrous material, as old paper stock, and fibrous material, as fabrics of all sorts. The non-fibrous material reduces more rapidly than the fibrous material, which resulted, under the old practice of keeping all the stock in reduction the same length of time, in over reduction of the non-fibrous material and, accordingly, in impairing the quality of the finished product.

In more recent years the most approved practice is to separate the fine material from the coarse continuously, as the desired state of reduction of the fine material is arrived at, while reduction is in progress, which serves to prevent over reduction of the non-fibrous material, and also lends itself readily without added manufacturing cost to producing two grades of pulp,—first grade fibrous pulp for making the finer grades of paper and second grade non-fibrous pulp for making the common grades of paper.

Various forms of reduction apparatus consisting of two or more units, as a stock breaker and finishing beater, or stock breaker, settling trough and finishing beater, or stock breaker, settling trough, screen and finishing beater, etc., arranged in coordinated relations for continuous production of pulp are now in use.

The improvements of the present invention relate to a stock beater, or beater engine, in which all the functions for producing pulp by continuous operation are combined in a single unit, thus simplifying both the apparatus and the process of reduction and, accordingly, effecting substantial economies in production costs.

In the accompanying drawings:

Fig 1, is a plan view illustrating a beater engine of the improved construction;

Fig. 2, is a broken sectional view taken on a line 2—2 of Fig 1;

Fig. 3, is a cross sectional view taken on a line 3—3 of Fig. 1;

Fig. 4, is a detail vertical sectional view taken on a line 4—4 of Fig. 1.

As here shown the reduction apparatus consists of a beater tub —1, a beater roll —2, supported on a drive shaft —3 and provided with blades or knives —4, arranged in the usual manner. Drive shaft —3 is supported on opposite sides of the tub in suitable brackets —5, and is adapted to be driven by a belt or pulley —6, the usual provision being made for raising and lowering the beater roll relative to the bed plate —7 by means of a worm gear arrangement —8. These features in various modified forms of construction are more or less common in beater construction and no novelty is claimed in respect thereto in connection with the present invention.

The beater tub is further provided at its opposite ends with weirs —9, and with a mid-feather —10, extending longitudinally through the center of the tub, water being supplied to the tub through a pipe —11. These features are also common in beater construction except as to the modifications which are features of the present improvements.

The improvements consist in a series of apertures —12, formed in the wall of the beater tub adjacent each weir —9, and apertures —13, formed in like manner in one of the walls of the mid-feather, which as here shown comprises two opposite walls —10, having a space —14, therebetween. Further improvements consist in a double series of apertures —15, and a plurality of slots —16, formed in the bottom of the tub, and a back-fall —17, in the usual relation to the beater roll. Secured to the bottom of the tub opposite each series of apertures —15 is a catch pan —18, and opposite each slot —16, a catch pan —19, provided respectively with drain valves —20 and —21, and connected to the bottom of space —14, of the mid-feather is a drain pipe —22,

provided with a valve —23, each of the weirs —9 being provided in like manner with a drain pipe —24, provided with a valve —25.

5 From the foregoing detailed description of the construction of the improved beater the following explanation of the operations of reduction will be readily understood;

Raw stock is supplied to the beater tub 10 by any suitable means, as an overhead chute or conveyor, water to mix with the stock in the desired quantity being supplied through pipe —11. The stock is kept in motion in the tub, by the action thereon of the beater 15 roll, the stock flowing around the mid-feather and passing between the beater roll and the bed plate and over the back-fall, which gives it added momentum, continuously until the required state of reduction 20 is arrived at.

Portions of the stock, as old paper and light fabrics having a low percentage of fibrous material, will be reduced to the required state by the hydration of the stock 25 and the action thereon of the beater roll, in much shorter time than other portions of the stock, as the heavier fabrics of all kinds, having a high percentage of fibrous material. It is desirable to remove the fine stock 30 from the mass in process of reduction continuously as the required state of fineness is arrived at, to prevent over reduction of any part of the stock. To this end the apertures —12, and —13, are provided to 35 cause the fine stock to separate from the coarse, and to pass through the apertures into weirs —9, and the space —14, of the mid-feather.

The fine stock entering the midfeather 40 chamber rises to the same level as the stock in the tub and returns to the apertures 13 at the higher levels, due to the constant agitation and movement of the stock, to the pulp mass floating in the tub, the perforated 45 wall of the midfeather acting as a screen for grading the stock. The fine stock entering the chambers 9 overflows the rim of the weirs and is conducted to any suitable apparatus, as a pump, for conveying the finished stock to other units of the reduction 50 apparatus, as a stuff chest or thickener. As in the case of the perforated midfeather wall, the perforated end walls of the beater tub also act as screens for grading the stock, 55 the arrangement as a whole being in effect a reduction apparatus adapted for continuous operation in which the finished stock is separated from the mass without interrupting the reduction process on the unfinished 60 portions of the stock, the arrangement being also effective to prevent over reduction of the finished stock.

The coarse material remaining in the tub 65 will be in further reduction until it is brought to the required state of fineness to

pass from the tub through the grading apertures, additional raw stock being supplied as required to keep the supply in the tub at normal.

Heavy substances foreign to pulp material, 70 as sand, fragments of rock and glass, pieces of metal, etc., will gravitate to the bottom of the tub, coarse substances passing through the slots —16, into catch pans —19, and fine materials passing through the slots —16, 75 and also through apertures —15, into catch pans —18. The deposits in pans —18, and —19, can be removed therefrom through suitable valves —20, and —21.

Having described my invention, I claim: 80

1. A continuous beater including in combination with a tub for mixing the raw stock in water, a beater roll operable in the tub for reducing the stock, a mid-feather comprising opposite walls forming a receptacle, and an outward extension of the tub forming a receptacle, apertures opening from the tub into said receptacles, whereby portions of the material reduced to a given state and floating at various levels will 90 separate from the mass of the material in the tub and pass through said apertures into said receptacles.

2. A continuous beater including in combination with a tub for mixing the raw stock in water, a beater roll operable in the tub for reducing the stock, a series of apertures formed in the wall of said tub along the course of the flow of the stock therein, and apertures formed in the bottom of the tub, whereby portions of the material reduced to a given state will separate from the mass of material in the tub and gravitate through the apertures in said wall and heavy substances foreign to pulp material will gravitate through the apertures in the bottom of the tub.

3. A continuous reduction apparatus comprising a beater tub, a beater roll operable in the tub, a weir adjacent the tub adapted to overflow with stock received from the tub, and a perforated wall between the tub and weir acting to grade the stock passing from the tub to the weir.

4. A continuous reduction apparatus comprising a beater tub, a beater roll operable in the tub, a chambered portion arranged relative to the tub adapted to overflow with stock received from the tub, and a perforated wall between said chambered portion and the stock under course of reduction in the tub acting to grade the stock passing to said chamber.

5. A continuous reduction apparatus comprising a beater tub, a beater roll operable in the tub, a chambered portion arranged relative to the tub adapted to receive stock continuously from the tub and to overflow with stock so received, and a perforated wall between said chambered portion and the

stock under course of reduction in the tub further reduction thereof and an element acting to grade the stock passing to said chamber.

6. A continuous reduction apparatus comprising a beater tub, a beater roll operable in the tub, a chambered portion arranged relative to said tub adapted to overflow with stock received from the tub and to prevent

further reduction thereof and an element 10 interposed between said chamber and the stock under course of reduction in the tub acting to grade the stock passing to said chamber.

In testimony whereof, I affix my signature.

CHARLES W. SHARTLE.
